UNITED STATES PATENT OFFICE.

MAURICE MARY JOSEPH OWEN O'CONOR, OF BALLYBRACK, IRELAND.

BOTTLE AND ITS STOPPERING.

SPECIFICATION forming part of Letters Patent No. 626,557, dated June 6, 1899.

Application filed July 15, 1896. Serial No. 599,270. (No model.)

To all whom it may concern:

Be it known that I, MAURICE MARY JOSEPH OWEN O'CONOR, captain in the Third Battalion Connaught Rangers, a subject of the Queen of Great Britain and Ireland, residing at Ballybrack, in the county of Dublin, Ireland, have invented Improvements in Bottles and their Stoppering, of which the following is a specification.

10 The object of my invention is to provide more conveniently and effectually than by methods heretofore proposed against liquids or other products being fraudulently passed off upon the public as the goods of persons or firms other than those from whom they have really emanated; and my invention relates for this purpose to certain improvements, hereinafter described, in bottles of the kind so made that when once filled and stoppered 15 it is necessary in order to remove the contents to so mutilate the bottle that while it will or may still be capable of use as an ordinary bottle the fact that it has been so mutilated will be easily recognizable by an 20 intending purchaser knowing the characteristic of the bottle in which the particular article he is purchasing is bottled by the firm or person whose manufacture or product he is desirous of buying.

25 Now according to my invention that portion of the bottle-neck which is to receive the cork is made with a hole through it at one side and at the opposite side with an internal recess and a part of much less thickness than the remainder, and after a cork has been inserted there is driven into the cork through the said hole in the neck a barbed pin or blade, which is passed through the hole in the side of the neck and into and through the 30 cork, so that the point of the barbed pin or blade projects into the recess in the opposite side of the neck. The cork or stopper may be pierced with a suitable sharp instrument preparatory to insertion of the barbed pin or blade.

35 Figure 1 of the accompanying illustrative drawings shows in central vertical section part of a bottle-neck embodying my invention. Fig. 2 is a modification.

40 Referring to Fig. 1, *a* is the ordinary part of the neck with thickened upper part or rim *b*. *c* is a part, which may be round or of

other form, of the wall of the neck made much thinner than the rest, and *d* is a normally-closed hole or recess inside the neck. 55 *e* is a hole through the wall of the neck at the opposite side. *f* is a cork forced into the neck as usual, and *g* is a pin or thin blade pointed at its forward end, and *h h* are rearwardly-directed barbs. After the cork has 60 been forced into place the barbed pin or blade is driven point foremost through the cork and with its pointed end into the hole or recess *d*. The barbs prevent the pin or blade being drawn back. To withdraw it, the thin part *c* 65 of the wall of the bottle-neck has to be broken and the projecting point of the pin or blade being then seized by any suitable instrument can be pulled out, thus enabling the cork to be withdrawn from the bottle in the ordinary 70 way.

The invention can be applied to stoppers of hard material as well as to stoppers of soft material, such as cork, the stoppers being in such cases formed with a transverse hole 75 through them. Fig. 2 shows the invention applied to a screw-stopper of hard material. The hole *i* is at the end adjacent to the hole *e* in the bottle-neck enlarged, as shown, to permit barbs on the pin or blade to open out 80 and bear against the inner side of the bottle-neck, as shown, and so prevent the withdrawal of the pin or barb. As will be seen, the arrangement in this case is such that only the thin part *c* of the wall, which is of comparatively small area, will be broken through, so that when the fact that the bottle has been 85 mutilated is easily recognizable its neck will not be broken off or be so damaged as to prevent the bottle from being used as an ordinary 90 bottle.

What I claim is—

1. A bottle-neck having diametrically arranged holes in opposite sides of its wall, one of said holes extending entirely through the 95 wall at one side and the other only partly through said wall at the opposite side and closed by a part of the bottle-neck of less thickness than the adjacent portion of the bottle-neck, substantially as described for the purpose specified.

2. A bottle-neck having two diametrically arranged holes *d* and *e* in line with each other and of which *e* passes completely through one

side of the bottle-neck and *d* is closed at its outer end by a thin wall or layer *c*, said thin wall or layer being flush or approximately flush with the outer surface of the bottle-neck 5 and capable of being easily perforated, without liability of breaking off the bottle-neck, by a pin forced endwise through the said holes and bottle-stopper, substantially as described.

3. A bottle having its neck formed at one 10 side with a hole and at the opposite side with an internal recess, a stopper located in said bottle-neck, and a barbed pin having its respective ends located in said hole and recess and its barbs pointing in the direction of said 15 hole, substantially as described for the purpose specified.

4. The combination of a bottle-neck having a part of less thickness than the rest of the 20 wall of said neck, a recess in the inner surface of the neck next to said thin part, a hole through the opposite side of the neck, a stopper having a hole therethrough in line with 25 said recess and hole in the bottle-neck, one end of hole in said stopper being enlarged, and a barbed pin extending through said stopper and projecting at one end into said

recess and at the other end into said hole in the bottle-neck, the barbs of said pin being flexible and having a natural tendency to spring outwardly and the hole in the bottle-neck being of less size than the barbed pin, when the barbs therein are in their extended positions, substantially as described for the purpose specified. 30

5. The combination in a bottle-neck of a part of less thickness than the rest of the wall of said neck, a recess in the inner surface of the neck next to said thin part, a hole through the opposite side of the neck a cork and a barbed pin extending through said cork and 40 projecting at one end into said recess and at the other end into said hole in the bottle-neck substantially as described for the purpose specified.

In testimony whereof I have signed my name to this specification in the presence of the two subscribing witnesses. 45

MAURICE MARY JOSEPH OWEN O'CONOR.
